(57) CLAIM

The ornamental design for an item holder for use with an air conditioning system, as shown and described.

DESCRIPTION

FIG. 1 is a perspective view of the item holder for use with an air conditioning system in full lines.

FIG. 2 is a rear elevational view thereof.

FIG. 3 is a front elevational view thereof.

FIG. 4 is a top plan view thereof.

FIG. 5 is a bottom plan view thereof.

FIG. 6 is a right side elevational view thereof.

FIG. 7 is a left side elevational view thereof; and,

FIG. 8 is an alternate perspective view thereof shown with environment.

The broken lines showing in FIG. 8 are for the purposes of illustrating the environment of the article only and form no part of the claimed design.

1 Claim, 5 Drawing Sheets*FIG. 1*
